UNITED STATES PATENT OFFICE.

THEOPHILUS M. RAWLS AND ROBERT A. MILLER, OF DUBLIN, TEXAS.

WINDOW SHADE, CURTAIN, AND DRAPERY HANGER.

1,130,929.

Specification of Letters Patent.

Patented Mar. 9, 1915.

Application filed July 27, 1914. Serial No. 853,358.

To all whom it may concern:

Be it known that we, THEOPHILUS M. RAWLS and ROBERT A. MILLER, citizens of the United States, residing at Dublin, in the 5 county of Erath, State of Texas, have invented a new and useful Window Shade, Curtain, and Drapery Hanger, of which the following is a specification.

The present invention appertains to a 10 hanger or fixture for supporting a window shade, curtain and drapery, and aims to provide a novel and improved device of that character.

The present invention contemplates the 15 provision of a hanger or fixture of the nature indicated, embodying a unique assemblage or component parts, and improved generally in its construction, to enhance the utility of the device, and to render the device 20 adjustable to accommodate various windows and window shades.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made 30 within the scope of what is claimed, without departing from the spirit of the invention.

The invention has been illustrated in its preferred embodiment in the accompanying drawing, wherein:—

35 Figure 1 is a front view of the device, parts being broken away. Fig. 2 is a plan view of the device, parts being broken away. Fig. 3 is an end view, and Fig. 4 is a sectional detail taken on the line 4—4 of Fig. 3.

40 In carrying out the present invention, there is provided an extensible or adjustable flat member 1 comprising a pair of bars or strips 2 and 3 of suitable length and thickness, and overlapped, the edges of the 45 rearmost bar or strip 2 being equipped with reflexed or bent back lips 4 forming a slide-way or guide which receives the bar or strip 3, to slidably connect the two strips.

To the ends of the extensible member 1, 50 is attached a pair of end pieces or brackets 5, preferably stamped from sheet metal of suitable gage, and of suitable contour. In order to attach the ends of the extensible member 1 and rear or basal ends of the end pieces 5 together, the remote ends of the bars or sections 2 and 3 of the member 1 are re-

flexed or bent back rearwardly, as at 6, and the end pieces 5 rest against the bends formed by the bent back ends 6 and have their rear or basal ends bent inwardly or angularly and reflexed, as at 7, so as to extend 60 around and within and to interlock with the reflexed ends 6 of the bars 2 and 3. The interfitting reflexed portions 6 and 7 are locked tightly together by punched or struck portions 8, which prevent the member 1 and end pieces 5 from shifting or sliding vertically so as to become detached.

As a means for applying the extensible member 1 to the lintel or upper end of a 70 window casing or frame, there is employed a pair of screws or nails 9 adapted to be driven or engaged into the lintel adjacent the lower edge of the member 1 and having angular upturned shanks 10 adapted to receive the bars 2 and 3 therebehind, to hold the said bars snugly against the face of the lintel. The bars 2 and 3 are adapted to seat upon the screws or nails 9 behind the upturned shanks 10 and the upper ends of the 80 shanks 10 are preferably provided with heads 11 to engage over the upper edges of the bars 2 and 3 to retain them in place. The screws or supporting elements 9 are preferably disposed adjacent the reflexed 85 and offset ends 6 of the bars 2 and 3, as illustrated in Figs. 1 and 2.

The end pieces or brackets 5 are adapted to accommodate an ordinary shade roller of 90 various lengths, and to this end, the end pieces 5 are provided adjacent their rear or butt ends, with apertures 12 and 13, respectively, one of which is circular, and the other of which is elongated, so that they may 95 accommodate the terminals of the shade roller, it being evident that when the extensible member 1 is extended, the shade roller may be readily applied between the end pieces 5, and then by contracting the member 1, the terminals of the shade roller may 100 be engaged into the apertures 12 and 13 to properly support the shade.

The end pieces 5 are provided at their forward or free ends with upturned ears 14 which are provided with central apertures 105 or openings 15, and between the ears 14 and apertures 12 and 13, the end pieces 5 are provided with circular openings or seats 16 having upwardly-projecting or inclined slots 17 leading therefrom to the upper edges 110 of the end pieces. The slots 17 are slightly narrower than the diameter of the openings

or seats 16, for the retention of the tubular curtain pole 18 within the openings or seats 16, as will hereinafter appear. The openings or apertures 15 of the ears 14 are adapted to receive a tubular drapery pole 19, and socketed ornamental heads 20 are adapted to be slipped over the protruding ends of the curtain and drapery poles 18 and 19.

In order to retain the pole 18 properly within the seats or openings 16, the pole 18 is preferably provided adjacent its ends, with outstruck opposed stops or lugs 21 having slots 22 therebetween. The stops or lugs 21 are adapted to engage the opposite sides or faces of the end pieces 5, to prevent the longitudinal shifting of the curtain pole 18, and the slots 22 enable the curtain pole 18 to be readily slid through the slots 17 into and out of the openings or seats 16, when the curtain pole 18 is rotated to the proper position, as will be apparent. The lugs or stops 21 at the opposite ends of the curtain pole 18, are preferably reversed, or project in opposite directions, as seen in Fig. 1, in order that one pair of lugs 21 will always engage or straddle the edge of one opening or seat 16, to prevent the longitudinal movement of the curtain pole 18.

In order to prevent the longitudinal movement of the drapery pole 19, the same is preferably provided at one end with a pair of opposed outstruck stops or lugs 23, which are arranged to be snapped through one or the other of the apertures 15, when the drapery pole 19 is inserted longitudinally through the ears 14, and in order that the stops 23 may engage the opposite sides of one of the end pieces 5, as seen in Fig. 1, to hold the pole 19 against accidental longitudinal shifting. It is to be noted that each pair of stops have outstanding shoulders facing each other and inclined faces extending from the surface of the pole toward each other to the shoulders, whereby the shoulders are engageable with the opposite sides of one of the brackets to hold the pole against longitudinal movement, and where by the said inclined faces enable the stops

to snap through the openings of the brackets. From the foregoing, taken in connection with the drawing, it is apparent that the present fixture may be employed for supporting in spaced relation, a window shade, curtain and drapery, and that the present device may be adjusted to accommodate various widths of windows, as well as various lengths of shade rollers and curtain and drapery poles. The construction of the present device is such that it is simple and light, and is adapted to take up the strains to which it is subjected, in an efficient manner. It is also manifest that the shade roller may be readily applied to and removed from the fixture, and that the curtain and drapery poles may be readily adjusted and removed from the fixture independently of each other.

The several parts may be constructed in various sizes and materials, and other alterations may be made within the scope of the appended claim, without departing from the spirit of the invention.

Having thus described our invention, what is claimed as new is:—

In a device of the character described, a pair of brackets having apertures, and a tubular pole fitting in the said apertures and having a pair of outstruck stops having outstanding shoulders facing each other and inclined faces extending from the surface of the pole toward each other to the shoulders, the shoulders being engageable with the opposite sides of one of the said brackets to hold the pole against longitudinal movement, and the said inclined faces enabling the stops to snap through the apertures of the brackets.

In testimony that we claim the foregoing as our own, we have hereto affixed our signatures in the presence of two witnesses.

THEOPHILUS M. RAWLS
ROBERT A. MILLER.
